PROCESS FOR THE PREPARATION OF CHLOROALKYL-S-ALKYL-AND ARYL- (D1) THIOL-PHOSPHORIC ACID DIESTER AND ESTER AMIDE CHLORIDES

This is a continuation-in-part application of U.S. application, Ser. No. 704,515, filed Feb. 12, 1968, now abandoned.

The present invention relates to and has for its objects the provision for particular new methods of producing chloroalkyl-S-alkyl- and -S-aryl- (di)thiolphosphoric acid diester and ester amide chlorides, which are known insecticide, fungicide and other plant protection agent intermediates, e.g. in a simple and uniform single step reaction, using readily available starting materials whereby to attain outstanding yields, with other and further objects of the invention becoming apparent from a study of the within specification and accompanying examples.

It is already known that 0,0-dialkyl-phosphorous acid diester chlorides (A) react with sulfenic acid chlorides (B) in the sense of the following equation to give O,S-thio-phosphoric acid diester chlorides (C) alkyl chloride being split off (cf. K. A. Petrov, G. A. Sokolskij and B. M. Polees, *Z. obsc. Chim.* 26, 3381 [1956]):

in which R is an alkyl radical, and R' is an alkyl or aryl radical.

In the case of the preparation of O-chloroalkyl-thiophosphoric acid diester chlorides (Ia), however, this process possesses the disadvantage that the 0,0-dialkyl-phosphorous acid diester chlorides (dialkylchlorophosphites) chlorinated in the alkyl radical which are required as starting materials are accessible only with difficulty.

Furthermore, thiol-phosphoric acid S-monoester amide chlorides (IB) can be obtained by reaction of O-alkyl-phosphorous acid ester dichlorides (C) with sulfenic acid amides (D) according to the equation:

(cf. K. A. Petrov, N. K. Bliznjik and V. A. Savosknok, *Z. obshch. Chim.* 31, 1361 [1961]), R and R' being the same as defined above, while R'' is a preferably lower, alkyl radical.

In this case, too, in the preparation of thiolphosphoric acid ester amides (Ib) with a 2- or 3-chloroalkyl group on the nitrogen atom, difficulty accessible starting materials are needed.

Finally, one-step processes for the obtaining of S,S-dithiophosphoric acid diester halides (Ic) with two different organic radicals have not up to now been described at all in the literature.

It has now been found, in accordance with the present invention, that chloroalkyl-S-alkyl- and -S-aryl-(di)thiophosphoric acid diester and ester amide chlorides, i.e. (O-, S- and N- chloroalkyl)-S-(alkyl, oxo-alkyl, phenyl and alkyl-, halo- and/or nitro-substituted phenyl)-diester chlorides and ester amide chlorides, having the general formula

in which R_1 , R_2 , R_3 , R_4 , R_5 and R_6 each respectively is selected from the group consisting of hydrogen, lower alkyl and chloro-lower alkyl, R_7 is selected from the group consisting of alkyl having one to 12 carbon atoms, oxo-substituted alkyl having one to 12 carbon atoms, halogen-substituted alkyl having one

to 12 carbon atoms, phenyl and substituted phenyl which is substituted with one to three substituents selected from the group consisting of lower alkyl, halo, nitro and mixtures of such substituents, X is selected from the group consisting of oxygen, sulfur, N-lower alkyl amino and N-phenyl amino, and *n* is a whole number from 0 to 1, with the proviso that R_3 and R_4 when taken together with the adjacently positioned carbon atom form a corresponding heterocyclic ring having the structure

in which X, R₁, R₂, R₅ and R₆ each respectively is the same as defined above, can be obtained much more simply and uniformly, that is in a one-step reaction, and with outstanding yields, by the process which comprises reacting 2-chloro-phospholane or -phosphorinane, i.e. 2-chloro-1,3-(dioxa, oxa-thia or oxa-aza)-2-(phospholane or phosphorinane) having the general formula

40 in which R_1 , R_2 , R_3 , R_4 , R_5 and R_6 , each respectively, X and n are the same as defined above, with alkyl or aryl sulphenyl chloride having the formula

45 in which R_7 is the same as defined above, whereby to form such corresponding chloroalkyl-ester chloride, if desired, in the presence of an inert organic solvent or diluent.

The smooth and uniform course of the novel process of the present invention is completely surprising. It could not in any way have been foreseen that the aforementioned 2-chlorophospholanes and -phosphorinananes would react with sulfinic acid chlorides with the splitting up of the heterocyclic ring and the formation of appropriate 2- or 3-chloroalkyl-thiophosphoric acid ester or ester amide chlorides.

55 Compared with the known methods mentioned above for the preparation of thiol- and dithiol-phosphoric acid ester and ester amide chlorides with chloralkyl radicals, the new process of the present invention is distinguished by a number of substantial advantages. These include, above all, ready accessibility 60 of the starting materials, uniform course of reaction, good yields and a very simple mode of performance.

If, for example, 2-chloro-1,3,2-dioxa-phospholane or dioxa-phosphorinane and methylsulfenic acid chloride are used as starting materials, the course of the reaction is illustrated by the following equation:

In the same manner, the reaction of 2-chloro-1,3,2-oxa-thia-phospholane with phenylsulfenic acid chloride proceeds in the sense of the equation:

Analogously, the reaction of 2-chloro-3-methyl-1,3,2-oxa-aza-phospholane with methylsulfenic acid chloride leads, according to the following equation to N,S-dimethyl-N-(2-chloroethyl)-thiolphosphoric acid monoester amide chloride:

Finally, the reaction of 4,9-dichloro-3,5,8,10-tetraoxa-4,9-diphospho-spiro-[5,5]-undecane with 4-tolylsulfenic acid chloride is represented by the following equation:

The 2-chloro-dioxa-phospholanes or -phosphorinanes and aliphatic or aromatic sulfenic acid chlorides usable as starting materials in accordance with the process of the invention are clearly defined by the appropriate general formulas (IIa), (IIc) and (IIb) stated above.

As examples of the phospholane or phosphorinane derivatives usable as starting materials in accordance with the process of the invention, there may be listed in particular 2-chloro-1,3,2-dioxa-, 2-chloro-4-methyl-1,3,2-dioxa-, 2-chloro-4,5-dimethyl-1,3,2-dioxa-, 2-chloro-5,5-dimethyl-1,3,2-dioxa-, 2-chloro-4,4,5,5-tetramethyl-1,3,2-dioxa-, 2-chloro-3-methyl-1,3,2-oxa-aza- and 2-chloro-1,3,2-oxa-thiaphospholane, and the like; and 2-chloro-1,3,2-dioxa-, 2-chloro-4-methyl-1,3,2-dioxa-, 2-chloro-4-propyl-5-ethyl-1,3,2-dioxa-, 2-chloro-5,5-dimethyl-1,3,2-dioxa-, 2-chloro-4-methyl-1,3,2-dioxa-phosphorinane, and the like; and 4,9-dichloro-3,5,8,10-tetraoxa-4,9-diphospho-spiro-[5,5]-undecane, and the like.

As examples of aliphatic sulfenic acid chlorides usable as starting materials herein there may be listed alkyl- and alkyl-sulfenic acid chlorides such as methyl, ethyl, n-propyl, isopropyl, n-butyl, isobutyl, sec.-butyl, n-amyl, isomyl, tert.-amyl, n-hexyl, 1,2,2-trimethyl-propyl, n-heptyl, n-octyl, n-dodecyl, and the like, sulfenic acid chlorides.

As examples of corresponding aromatic sulfenic acid chlorides usable herein there may be listed phenyl, 2-, 3- and

4-chloro-, 2-, 3- and 4-bromo, 2,4-, 3,4- and 2,5-dichloro, 2,4,5- and 2,4,6-trichloro, 2-, 3- and 4-methyl, 4-isopropyl, 2-chloro-4-methyl, 3-chloro-4-methyl, 3-methyl-4-chloro, 2-chloro-4-tert.-butyl, 2-, 3- and 4-nitro, 2- and 3-chloro-4-nitro, 2,5- and 3,5-dichloro-4-nitro, 2- and 3-methyl-4-nitro, 3-nitro-4-methyl, and the like, -phenyl sulfenic acid chlorides, and the like.

The starting 2-chloro-phospholane and -phosphorinane derivatives have already been described in the literature; they can readily be prepared, even on an industrial scale, by known methods from 1,2- or 1,3-glycols or the appropriate glycolene-mercapto-alkanols or glycolene N-alkyl- or N-aryl-amino-alkanols and phosphorus-(III)-chloride, for example:

The aliphatic or aromatic sulfenic acid chlorides required as starting materials are also readily accessible in known manner by reaction of the appropriate mercaptans or thiophenols with chlorine or sulfuryl chloride or by chlorinated splitting of their disulfides.

The process of the present invention can be carried out in the presence or absence of solvents (this term includes diluents). Practically all inert organic solvents (or diluents) and their mixtures are suitable. However, particularly good results have been obtained with aliphatic and aromatic hydrocarbons (optionally chlorinated), including lower aliphatic, especially lower alkyl, hydrocarbons, C₆-10 aryl, especially benzene, hydrocarbons, chlorinated lower aliphatic, especially chlorinated lower alkyl, hydrocarbons, chlorinated C₆-10 aryl, especially chlorinated benzene, hydrocarbons, such as methylene chloride, dichloroethane, di-, tri- and tetra-chloroethylene, chloroform, carbon tetrachloride, benzene, benzene, chlorobenzene, toluene and xylene; ethers, including aliphatic and cycloaliphatic ethers, such as lower aliphatic, especially lower alkyl, and lower cycloaliphatic ethers, for example diethyl and di-n-butyl ether, dioxan, tetrahydrofuran; aliphatic ketones and nitriles of low molecular weight, including lower alkyl ketones and lower alkanoyl acid nitriles, for example acetone, methylethyl ketone, methylisopropyl ketone and methylisobutyl ketone, acetonitrile and propionitrile; and the like.

The reaction according to the present invention can be carried out within a fairly wide temperature range, which may vary according to the nature of the starting materials to be reacted. In general, the work is preferably carried out at a temperature substantially between about -20° to +50° C., preferably at about -10° to +30° C.

In accordance with the process of the invention, 1 mol of 2-chloro-phospholane or -phosphorinane is expediently used per mol of sulfenic acid chloride, although an excess of one or the other reactant can still be used. In the case of a starting compound of the type contemplated by Formula (IIc), however, the sulfenic acid chloride will be expediently used in at least a 100 percent excess over the molar amount of the 2-chloro-phospholane or -phosphorinane present.

It has proved expedient to add the sulfenic acid chloride (if desired, diluted with one of the above-mentioned solvents) dropwise to a solution or suspension of the phospholane derivative or phosphorinane derivative at the above stated temperature, with stirring and possibly with cooling of the reaction mixture. After completion of the addition, the mixture is left to stand for about 1 to 3 hours, the solvent is then removed and the residue is subjected to fractional distillation.

The products of the instant process are in most cases colorless to yellow oils, some of which can be distilled under greatly reduced pressure without decomposition. If this is not possible, the compounds obtainable according to the invention can,

for the purpose of purification, be slightly distilled, that is, freed from the last volatile impurities by longer heating to slightly to moderately elevated temperatures under reduced pressure. Since, however, the reaction usually yields the compounds in high purity, their further reaction or use is possible without isolation and purification.

The chloroalkyl-S-alkyl or -S-aryl- (di)thiolphosphoric acid diester monochlorides or ester amide chlorides, which are formed as products in accordance with the production process of the present invention, and which are known in part from the literature, are valuable intermediate products which can be used in the known way for the preparation of insecticides, fungicides and other plant protection agents of the type as disclosed in copending U.S. application Ser. No. 727,697, filed simultaneously herewith, corresponding to German patent application F52369 IVb/12o, filed in Germany May 10, 1967, i.e. by reaction of the instant compounds, e.g. in an acid-binding agent such as sodium carbonate, methylamine, etc., with an appropriate alcohol, mercaptan, phenol, thiophenol or N-alkyl or N,N-dialkyl amine, or corresponding alkali metal or ammonium salt of such hydroxy or thiol compound, e.g. in the presence of an inert organic solvent such as methylene chloride, benzine, benzene, diethyl ether, acetone, acetonitrile, etc., at 20°-100° C., and recovering the final product, e.g. by pouring over ice, extracting with a solvent such as benzene, washing, drying and distilling.

Such final products contemplate chloroalkyl-thiolphosphoric acid esters and/or -ester amides of the general structure:

in which R_1 , R_2 , R_3 , R_4 , R_5 , R_6 , R_7 , X and n are the same as defined above, and $Y-R_8$ is the corresponding alcohol, mercaptan, phenol, thiophenol or amino group resulting from the splitting off of HCl (to achieve the condensed product), using a compound of the type $H-Y-R_6$.

The following examples illustrate the new production process for the present invention:

EXAMPLE 1

82.5 g. (1 mol) of methylsulfenic acid chloride dissolved in 200 ml. of tetrachloromethane are added dropwise at 20° to 30° C. to a solution of 126.5 g. (1 mol) of 2-chloro-1,3,2-dioxa-phospholane, i.e. 2-chloro-1,3-dioxa-2-phospholane, in 200 ml. of tetrachloromethane. After completion of the addition the mixture is left to stand for 1 hour at room temperature, the solvent is drawn off and the residue is distilled. The yield is 200 g. (96 percent of the theory). The O-(2-chloroethyl)-S-methyl-thiolphosphoric acid diester monochloride boils under a pressure of 1 mm. Hg at 106° C.

Analysis

Calculated for $C_3H_7O_2Cl_2SP$ (molecular weight 209.0): 15.33%
Found: 14.75%

EXAMPLE 2

138.6 g. (1 mol) of 2-chlorosulfonyl-isobutyraldehyde are added dropwise at 10° to 20° C. to a solution of 126.5 g. (1 mol) of 2-chloro-1,3,2-dioxa-phospholane, i.e. 2-chloro-1,3-dioxa-2-phospholane, in 300 ml. of dichloromethane. The mixture is then left to stand for 1 hour at room temperature, the solvent is drawn off and the residue is subjected to fractional distillation, the O-(2-chloro-ethyl)-S-(2-oxo-1,1-dimethyl-eth-1-yl)-thiolphosphoric acid diester monochloride coming over at 150° C. under a pressure of 0.4 mm. Hg. The yield is 204 g. (77 percent of the theory). The product has the refractive index $n_{D}^{20} = 1.5185$.

Analysis

	P	S
Calculated for $C_6H_{11}O_3PSCl_2$ (molecular weight 265.1):		
Found:	11.68%	12.08%
	11.52%	12.67%

EXAMPLE 3

158.5 g. (1 mol) of 4-tolylsulfenic acid chloride are added dropwise at 20° to 30° C. to a solution of 126.5 g. (1 mol) of 2-chloro-1,3,2-dioxa-phospholane, i.e. 2-chloro-1,3-dioxa-2-phospholane, in 400 ml. of dichloromethane and, after standing for 1 hour, the reaction mixture is worked up in the manner described in the preceding example. There is thus obtained O-(2-chloro-ethyl)-S-(4'-tolyl)-thiolphosphoric acid diester monochloride in the form of a nondistillable oil.

EXAMPLE 4

50 One hundred and seventy-nine grams (1 mol) of 4-chlorophenylsulfenic acid chloride are added at 30° C. to a solution of 154.5 g. (1 mol) of 2-chloro-4,5-dimethyl-1,3,2-dioxa-phospholane, i.e. 2-chloro-4,5-diemethyl-1,3-dioxa-2-phospholane, in 300 ml. of dichloromethane. The mixture is
 55 then left to stand for 1 hour at room temperature, the solvent is drawn off and the residue is distilled. The yield is 268 g. (80 percent of the theory). The $\text{O}-(3\text{-chlorobut-2-yl})\text{S}-(4'\text{-chlorophenyl})\text{-thiolphosphoric acid diester monochloride}$ comes over at 162° C. under a pressure of 1 mm. Hg and possesses the refractive index $n^{20}_{D} = 1.5617$.

Analysis

Calculated for $C_{10}H_{12}O_2Cl_3PS$ (molecular weight 333.6):		S
Found:		9.61%
		10.04%

EXAMPLE 5

189.5 g. (1 mol) of 2-nitrophenylsulfenic acid chloride are added at 25° C. to a solution of 154.5 g. (1 mol) of 2-chloro-4,5-dimethyl-1,3,2-dioxa-phospholane, i.e. 2-chloro-4,5-dimethyl-1,3-dioxa-2-phospholane, in 100 ml. of dichloromethane, and the reaction mixture, after standing for 1 hour, is worked up as described in the preceding example. In this way, O-(3-chloro-but-2-yl)-S-(2'-nitrophenyl)-thiolphosphoric acid diester monochloride is obtained as an oily substance which, even under greatly reduced pressure, cannot be distilled without decomposition. The yield is 244 g. (71 percent of the theory).

EXAMPLE 6

82.5 g. (1 mol) of methylsulfenic acid chloride dissolved in 200 ml. of tetrachloromethane are added dropwise at 0° C. to 139.5 g. (1 mol) of 2-chloro-3-methyl-1,3,2-oxa-aza-phospholane, i.e. 2-chloro-3-methyl-1-oxa-3-aza-2-phospholane. After the mixture has stood for 1 hour at room temperature, the solvent is drawn off and the residue is distilled. The N,S-dimethyl-N-(2-chloro-ethyl)-thiolphosphoric acid monoester monoamide monochloride boils at 128° C. under a pressure of 2 mm. Hg. The yield is 182.5 g. (82.0 percent of the theory).

Analysis

	P	S
Calculated for $\text{C}_4\text{H}_9\text{OCl}_2\text{PS}$ (molecular weight 222.1):	13.95%	14.44%
Found:	13.82%	15.00%

EXAMPLE 7

A solution of 82.5 g. (1 mol) of methylsulfenic acid chloride in 100 ml. of tetrachloromethane is added dropwise at 30° C. to 154.5 g. (1 mol) of 2-chloro-4-methyl-1,3,2-dioxa-phosphorinane, i.e. 2-chloro-4-methyl-1,3-dioxa-2-phosphorinane. The solvent is drawn off after brief standing of the mixture, and the residue is distilled. There are obtained in this manner 206 g. (87 percent of the theory) of O-(3-chlorobut-1-yl)-S-methyl-thiolphosphoric acid diester monochloride of b.p. 124° C./1 mm. Hg.

Analysis

	Cl	P	S
Calculated for $\text{C}_5\text{H}_11\text{O}_2\text{Cl}_2\text{PS}$ (molecular weight 237.1):	29.1%	13.06%	13.52%
Found:	29.70%	13.52%	13.81%

EXAMPLE 8

144.5 g. (1 mol) of phenylsulfenic acid chloride are added at 20° C. to 132.5 g. (0.5 mol) of 4,9-dichloro-3,5,8,10-tetraoxa-4,9-diphospho-spiro-[5,5]-undecane dissolved in 200 ml. of dichloromethane. The reaction mixture is then worked up in the manner already described in the preceding example and the product of the above formula is obtained in the form of an oil which cannot be distilled without decomposition. The yield is 175 g. (=59 percent of the theory).

EXAMPLE 9

20 One hundred and seventy-nine grams (1 mol) of 4-chlorophenylsulfenic acid chloride are added at 50° C. to a solution of 175 g. (1 mol) of 2-chloro-4-chloromethyl-1,3,2-dioxa-phospholane, i.e. 2-chloro-4-chloromethyl-1,3-dioxa-2-phospholane. The solvent is drawn off and the residue is distilled under reduced pressure. Three hundred and twelve grams (88 percent of the theory) of O-(1,3-dichloro-prop-2-yl)-S-(4'-chlorophenyl)-thiolphosphoric acid diester monochloride of boiling point 194° C./1 mm. Hg and refractive index $n_D^{20}=1.5765$ are obtained.

EXAMPLE 12

Upon repeating the procedure of example 1 using corresponding molar amounts of each of the following sulfenic acid chlorides with the appropriate 2-chloro-phospholanes and phosphorinane:

- 3-fluorophenyl sulfenic acid chloride and 2-chloro-3-phenyl-4,4-diisobutyl-5,5-diethyl-1-oxa-3-aza-2-phospholane;
- 4-bromophenyl sulfenic acid chloride and 2-chloro-3,6-di-sec.-butyl-4,5-di-methyl-4-tert.-butyl-1-oxa-3-aza-2-phosphorinane; and

c. 2-nitro-3-methyl-6-iodo-phenyl-sulfenic acid chloride and 2-chloro-4-ethyl-4-isopropyl-5-methyl-5-n-butyl-1-oxa-3-thia-2-phospholane; the corresponding final products are obtained:

- N-phenyl-N-[(1,1-diisobutyl-2-ethyl-2-chloro)-but-1-yl]-S-(3'-fluorophenyl)-thiolphosphoric acid monoester amide monochloride;
- N-sec.-butyl-N-[1,2,4,-tri-methyl-1-tert.-butyl-3-chloro)-hex-1-yl]-S-(4'-bromophenyl)-thiolphosphoric acid monoester amide monochloride; and
- S-[(1-ethyl-1-isopropyl-2-methyl-2-chloro)-hex-1-yl]-S-(2'-nitro-3'-methyl-6'-iodo-phenyl)-dithiolphosphoric acid diester monochloride.

The following examples illustrate the manner in which the instant compounds may be converted to and used as fungicidally active final products:

EXAMPLE 13

- 50
- 55 The preparation is carried out without isolation of the O-(3-chlorobut-2-yl)-S-(4'-chlorophenyl)-thiol-phosphoric acid diester monochloride of the formula
- 60
- 65 A solution of 154.5 g. (1 mol) 2-chloro-4,5-dimethyl-1,3,2-di-oxa-phospholane in 300 ml. dichloromethane is reacted with 178 g. (1 mol) 4-chlorophenylsulfenic acid chloride at 30° C. After standing for 1 hour at room temperature, 80 ml. (excess) methanol is added to the reaction mixture and heated until termination of hydrogen chloride evolution. Subsequently, the mixture is twice washed with ice water and thereafter once again with saturated sodium hydrogen carbonate solution, the organic phase separated and dried over sodium sulfate. The residue obtained after separation of the solvent is distilled under reduced pressure. The O-methyl-O-

- 75

(3-chloro-but-2-y)-S-(4'-chlorophenyl)-thiol-phosphoric acid ester has a boiling point of between 148 and 150° C./0.05 Torr. The yield amounts to 197 g. (60 percent of the theory).

Analysis:

	Cl	P
Calculated for $C_{11}H_{13}O_3PS$ (molecular wt. 329):	21.6%	9.4%
Found:	21.4%	9.7%

In analogous manner, upon use of 4-methylphenyl-sulfenic acid chloride, the O-methyl-O-(3-chlorobut-2-yl)-S-(4'-methylphenyl)-thiol-phosphoric acid ester of the formula 10

is obtained having a boiling point of 160° C./0.01 Torr. The yield amounts to 200 g. (65 percent of the theory).

Analysis:

	P	S
Calculated for $C_{11}H_{13}Cl_2O_3PS$ (molecular wt. 308.5):	10.0%	10.4%
Found:	99%	10.9%

Such final products possess strong fungitoxic effect and a broad range of activity. Despite this excellent effect in combating phytopathogenic fungi, they are only slightly toxic to 25 warmblooded animals (average toxicity DL_{50} in the rat per os 100 to 1000 mg./kg. animal), and are excellently compatible with higher plants. Due to these properties, the final products are excellently suited for use as plant protecting agents in combating fungus diseases, and specifically for combating 30 fungi of a great variety of classes, for example, *Archimycetes*, *Phycomycetes*, *Ascomycetes*, *Basidiomycetes*, *Fungi imperfecti*, and the like. Such final products have proven to be particularly effective, however, in combating fungus diseases on rice plants, particularly fungus disease caused by *Piricularia oryzae*. These final compounds exhibit excellent protective and curative activity in combating particularly this fungus. 35

In addition, such final compounds may be used also for purposes of combating other fungus pathogens on rice and other cultivated plants, and are particularly effective against the fol- 40

lowing fungus species: *Corticium sasakii*; *Cochliobolus miyabeanus*; *Mycosphaerella species*; *Corticium species*; *Ceropora species*; *Alternaria species*; *Botrytis species*, and the like.

5 Furthermore, such final compounds exhibit very good fungicidal activity with respect to fungi which attack the plant from the soil and partially those which cause tracheomycoses, such as for example: *Fusarium cubense*; *Fusarium dianthi*; *Verticillium alboatratum*, and *Phialophora cinerescens*.

EXAMPLE 14

Piricularia Test/Preparation of liquid active substance

15 Solvent:	1 part by weight acetone
Dispersing agent:	0.05 part by weight sodium oleate
Additive:	0.2 part by weight gelatin
Water:	98.75 parts by weight water.

20 The quantity of the active substance necessary to obtain the desired concentration of active substance in the spray liquid, is admixed with the stated amount of solvent, and the resulting concentrate is diluted with the stated amount of water which contains the stated dispersing agent and additive.

The spray liquid is sprayed onto 30 rice plants which are about 14 days old until they are dripping wet. Until they are dry, the plants remain in a hothouse at temperatures from 22° to 24° C. and a relative humidity of about 70 percent. Thereafter, they are inoculated with an aqueous suspension of 100,000 to 200,000 spores/ml. of *Piricularia oryzae* and stored in a room at a temperature between 24°-26° C. and a relative humidity of 100 percent.

Five days after the inoculation, infection is determined on all leaves present at the time of inoculation as a percent of the untreated but also inoculated control plants. 0 percent means no infection, 100 percent means that infection is as high as in the control plants.

The active substances tested, their concentrations and the results obtained are shown in the following table:

NOTE.—Pr.=protective effect; Cur.=curative effect.

DETERMINATION OF THE CURATIVE EFFECT

In the above-mentioned test including the preparation of the liquid active substance, there is determined not only the protective but also the curative effect of the active compounds. Determination of the curative effect deviates from the above-described test procedure (which only supplies data regarding the protective effect) in that the active compounds are applied not prior to but 16 hours after the inoculation. Compounds which in this type of test procedure shown activity, are capable of killing the fungus after infection and thereby have a curative effect.

Advantageously, in accordance with the present invention, in the foregoing formulae,

R₁, R₂, R₃, R₄, R₅ and R₆ each respectively represents

hydrogen;

lower alkyl such as methyl, ethyl, n- and isopropyl, n-, iso-, sec.- and tert.-butyl, and the like, especially C₁₋₄ alkyl, and particularly methyl; or

chloro-lower alkyl, especially chloro-C₁₋₄ alkyl, and particularly chloromethyl;

R₇ represents

straight and branched alkyl having one to 12 carbon atoms, such as methyl to tert.-butyl inclusive as defined above, n-, iso- and tert.-amyl, n-hexyl, 1,2,2-trimethyl-propyl, n-heptyl, n-octyl, n-nonyl, n-decyl, n-undecyl, n-dodecyl, and the like, especially lower alkyl, more especially C₁₋₄ alkyl, and particularly methyl;

such alkyl which is substituted with an oxo group (||), i.e. carbonyl or aldehydo-containing C₁₋₁₂ alkyl as defined above, especially carbonyl substituted lower alkyl, and more especially carbonyl substituted C₁₋₄ alkyl;

halogen-substituted alkyl having one to 12 carbon atoms, including chloro, bromo, iodo and/or fluoro-C₁₋₁₂, preferably—C₁₋₄ alkyl, especially mono-halo-substituted C₁₋₄ alkyl, and particularly chloro and bromo substituted C₁₋₄ alkyl;

phenyl; or

substituted phenyl which is substituted with one to three (same or mixed) substituents in ortho, meta and/or para positions including

lower alkyl such as methyl to tert.-butyl inclusive as defined above, especially C₁₋₄ alkyl, and particularly methyl;

halo such as chloro, bromo, iodo and/or fluoro, especially 1-3 chloro, and particularly monochloro; and/or

nitro;

X represents

oxygen;

sulfur;

N-lower alkyl amino such as N-monomethyl to

tert.-butyl inclusive as defined above, -amino, especially N—C₁₋₄ monoalkyl amino; or

N-phenylamino; and

n is a whole number from 0 to 1;

with the proviso that R₃ and R₄ when taken together with the adjacently positioned carbon atom form a corresponding heterocyclic ring moiety having the structure

in which X is oxygen, R₁, R₂, R₅ and R₆ each respectively is

35 hydrogen.

It will be appreciated that the instant specification and examples are set forth by way of illustration and not limitation, and that various modifications and changes may be made without departing from the spirit and scope of the present invention which is to be limited only by the scope of the appended claims.

What is claimed is:

1. Process for the production of chloroalkyl-S-alkyl and -S-phenyl- (di)thiolphosphoric acid ester chlorides having the 45 formula

in which R₁, R₂, R₃, R₄, R₅ and R₆ each respectively is selected from the group consisting of hydrogen, lower alkyl and chloro-lower alkyl, R₇ is selected from the group consisting of alkyl having one to 12 carbon atoms, oxo-substituted isobutyl, halogen-substituted alkyl having one to 12 carbon atoms, phenyl and substituted phenyl which is substituted with one to three substituents selected from the group consisting of lower alkyl, halo, nitro and mixtures of such substituents, X is selected from the group consisting of oxygen, sulfur, N-lower alkyl amino and N-phenyl amino, and n is a whole number from 0 to 1; with the proviso that R₃ and R₄ when taken together with the adjacently positioned carbon atom form a corresponding heterocyclic ring having the structure

70 in which X is oxygen and R₁, R₂, R₅ and R₆ each respectively is hydrogen which comprises reacting a 2-chloro-1-oxy-phosphorous compound having the formula

in which R_1 to R_6 , X and n are the same as defined above, with a sulfonyl chloride having the formula

in which R_7 is the same as defined above, whereby to form such corresponding chloroalkyl-ester chloride.

2. Process according to claim 1 wherein the reaction is carried out at a temperature substantially between about -20° to 20 $+50^\circ$ C.

3. Process according to claim 2 wherein said reaction is carried out in the presence of an inert organic solvent.

4. Process according to claim 2 wherein said reaction is carried out in the presence of an inert organic solvent selected from the group consisting of aliphatic hydrocarbon, chlorinated aliphatic hydrocarbon, aromatic hydrocarbon, chlorinated aromatic hydrocarbon, aliphatic ether, cycloaliphatic ether, aliphatic ketone, aliphatic nitrile, and mixtures thereof.

5. Process according to claim 4 wherein said solvent is selected from the group consisting of lower alkyl hydrocarbon, chlorinated lower alkyl hydrocarbon, benzene hydrocarbon, chlorinated benzene hydrocarbon, lower alkyl ether, lower cycloaliphatic ether, lower alkyl ketone, lower alkanic acid nitrile, and mixtures thereof.

6. Process according to claim 2 wherein the reactants are present in substantially about equimolar amounts.

7. Process according to claim 2 wherein n is 1, R_3 and R_4

form with the adjacently positioned carbon atom said heterocyclic ring and wherein said sulfonyl chloride is present in substantially about a 100 percent molar excess over the amount of the corresponding 2-chloro-1-oxy-phosphorus compound present.

8. Process according to claim 2 wherein R_1 , R_2 , R_3 , R_4 , R_5 and R_6 , each respectively is selected from the group consisting of hydrogen, C_{1-4} alkyl and chloromethyl, R_7 is selected from the group consisting of C_{1-4} alkyl, monooxo-substituted C_4 alkyl, monohalogen-substituted C_{1-4} alkyl, phenyl, C_{1-4} alkyl-substituted phenyl, chloro-substituted phenyl and nitro-substituted phenyl, X is selected from the group consisting of oxygen, sulfur and $N-C_{1-4}$ -monoalkyl-amino, and n is a whole number from 0 to 1, with the proviso that R_3 and R_4 when taken together with the adjacently positioned carbon atom form a corresponding heterocyclic ring having the structure

25 in which X is oxygen and R_1 , R_2 , R_3 and R_4 each respectively is hydrogen.

9. Process according to claim 8 wherein n is 0.

10. Process according to claim 8 wherein n is 1.

30 11. Process according to claim 2 wherein R_1 , R_2 , R_3 , R_4 , R_5 and R_6 , each respectively, is selected from the group consisting of hydrogen and methyl, R_7 is selected from the group consisting of phenyl, 4-chlorophenyl and C_{1-4} alkyl, X is selected from the group consisting of oxygen, sulfur and $N-C_{1-4}$ -monoalkylamino, and n is a whole number from 0 to 1.

12. Process according to claim 11 wherein R_1 is methyl, R_2 , R_3 , R_4 , R_5 and R_6 each respectively is hydrogen and X is oxygen.
